DESIGN FOR A CLOCK CASE

Othneil G. Williams, Winsted, Conn., assignor to William L. Gilbert Clock Corporation, Winsted,
Conn., a corporation of Connecticut

Application November 20, 1936, Serial No. 66,043

Term of patent 3½ years

To all whom it may concern:

Be it known that I, Othneil G. Williams, a citizen of the United States, residing at Winsted, in the county of Litchfield, State of Connecticut, have invented a new, original, and ornamental Design for a Clock Case, of which the following is a specification, reference being had to the accompanying drawing, forming a part thereof.

In the accompanying drawing, the figure is a perspective view of a clock case showing my new design.

I claim:

The ornamental design for a clock case, as shown.

OTHNEIL G. WILLIAMS.
